(57) **CLAIM**

The ornamental design for a motor assembly as shown and described.

DESCRIPTION

FIG. 1 is a perspective view of a motor assembly showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view thereof; and,

FIG. 9 is third perspective view showing the motor assembly.

The broken lines shown in the figures are for the purpose of illustrating portions of the motor assembly and form no part of the claimed design.
